F. H. SCHULTZ.
FLYING TOY GUN.
APPLICATION FILED OCT. 9, 1920.

1,382,560.

Patented June 21, 1921.

UNITED STATES PATENT OFFICE.

FERDINAND H. SCHULTZ, OF TREYNOR, IOWA.

FLYING-TOY GUN.

1,382,560.

Specification of Letters Patent. Patented June 21, 1921.

Application filed October 9, 1920. Serial No. 415,731.

To all whom it may concern:

Be it known that I, FERDINAND H. SCHULTZ, a citizen of the United States, and a resident of Treynor, in the county of Pottawattamie and State of Iowa, have invented 5 a certain new and useful Flying-Toy Gun, of which the following is a specification.

The object of my invention is to provide a flying toy gun of a kind adapted to im- 10 part a rapid whirling movement to a flying toy.

With this and other objects in view, my invention consists in the construction, arrangement and combination of the various 15 parts of my device, whereby the objects contemplated are attained, as hereinafter more fully set forth, pointed out in my claims, and illustrated in the accompanying drawings, in which:

20 Figure 1 shows a longitudinal, central, sectional view through a flying toy gun embodying my invention, taken on the line 1—1 of Fig. 5.

Fig. 2 shows a detail, sectional view taken 25 on the line 2—2 of Fig. 1.

Fig. 3 shows an end elevation of the gun with the flying toy installed thereon.

Fig. 4 is a detail, sectional view taken on the line 4—4 of Fig. 5.

30 Fig. 5 is an elevation of the discharge end of the gun.

Fig. 6 is a detail, sectional view taken on the line 6—6 of Fig. 1; and

35 Fig. 7 is an elevation of the gun with the toy installed thereon ready for use.

In the accompanying drawings, I have used the reference numeral 10 to indicate generally a tubular member, forming a portion of my improved flying toy gun.

40 At the discharge end of the tubular member 10 the wall is slit and the opposite sides are extended outwardly, as at 11, forming spaced walls or flanges, shown in Figs. 1, 2 and 5.

45 It will thus be seen that the end of the tubular member 10 forms substantially a channel, as shown at A in Fig. 2.

A U-shaped frame member is mounted on said end, as indicated at 12 in Fig. 3, and 50 projects beyond the flanges 11 as shown.

The arms of the frame member 12 at each edge of each arm are provided with laterally extending flanges 13, which also project beyond the ends of said arms, as shown in 55 Fig. 2.

The two outer flanges 13 beyond the arms

of the member 12 are connected by a cross plate 14 and the two inner flanges are similarly connected by a cross plate 15.

Extended through the plates 14 and 15 and the respective flanges and spaced from each other are spindles or shafts 16 and 17, on which are mounted rollers 18. The plates 14 and 15 are provided with alined arms 19 and 20 through which loosely projects a 65 spindle or shaft 21 on the outer end of which is a block 22.

The plate 14 is provided with a tooth or shoulder 23.

Adjacent to the plate 14 on the shaft or 70 spindle 21 is a disk 24, having a series of projecting engaging members or teeth 25 adapted to coact with the shoulder or tooth 23, so as to permit the disk 24 to be rotated freely in one direction with the teeth 25 sliding over the tooth 23 and to permit one of the teeth 25 to engage the tooth 23 and prevent further rotation of the disk 24 and the block 22 and shaft 21 in the other direction, when the shaft 21 is longitudinally moved 75 to position for causing the proper engagement of the teeth.

What may be called the outer end of the shaft 21 projects substantially through the block 22 and is slightly tapered, as at 80 85

A shaft 27 is mounted in the walls or flanges 11 and supported thereon is a pulley 28. Secured to the spindle or shaft 21 is a cord or flexible device 29, which is extended over the pulley 28 and thence into the tubular member 10. The cord 29 is secured to a strong spring 30.

On the end of the tubular member 10 farthest from the pulley 28 is slipped a cap 31. A rod 32, screw-threaded near its ends 95 and having a smooth exterior over its central portion, is screwed into the cap 31, as shown in Fig. 1 and is pivoted to the arms of a U-shaped fastening member 33, to which is connected the spring 30.

On the outer end of the rod 32 is a head 34. Slidably mounted on the smooth portion of the rod 32 is a disk or the like 35. Extending away from the plate 15 are spaced ears 36, through which there extends 105 a short shaft 37.

A trigger device 38 has opposite flanges 39 received between the arms 36 and mounted on the shaft 37.

One end of the trigger device 38 stands adjacent to one end of the spindle or shaft 21 and the other end thereof projects through a 110

slot into the tubular member 10, as shown in Fig. 1.

Secured to the latter end of the trigger device 38 is a string or the like 40, extending through the tubular member 10 and through a hole in the cap 31. The string 40 is then secured to the disk 35, which slides freely on the rod 32.

For use with my gun herein described, I provide a flying toy comprising a substantially rectangular strip of metal, having a central portion 41 and spaced opposite wings 42. The forward edges of the wings at their portions adjacent to the central portion 41 are provided with shoulders 43.

The flying toy just mentioned is preferably of the type described in my co-pending application, Serial No. 415,730, filed Oct. 9, 1920.

In the practical use of my improved gun, the flying toy is placed on the block 22 with one edge of the toy adjacent to a lug 44 on the block 22 and with the end 26 of the spindle or shaft 21 extending through a hole 45 at the center of the toy. The gun is then inclined for instance as shown in Fig. 7. The bottom end of the gun is then preferably placed on the floor or ground, and the operator grasps the tubular member 10 and the block with the toy thereon, thereby holding the spindle 21 at its limit of its movement toward the handle of the gun, whereupon the tubular end of the member 12 can be turned as a crank around the block easily and conveniently for winding the flexible member 29 on the shaft 21 for thereby stretching the spring 30. Whenever the grip of the hand or fingers on the toy and block is released, one of the shoulders or teeth 25 will engage the tooth 23 for preventing the unwinding of the flexible device by the spring until the trigger device is released.

The operator then grasps the disk 23 and pulls it toward the head 34, thereby moving the trigger device 38 for forcing the shaft 21 longitudinally a sufficient distance to cause the tooth 25 to clear the tooth or lug 23, whereupon the spring 30 will contact for imparting a rapid rotating movement to the shaft 21 and the block 22 and the flying toy.

The flying toy will then fly into the air for a considerable distance, and the gun is ready for use again. The rollers 18 form bearing for the shaft or spindle 21, so as to permit the free rotation thereof. A spring 46 yieldingly holds the trigger device 38 in such position that it does not interfere with the operation of the shaft 21 and the engaging of the members 25 and 23.

It is my purpose to cover by my claims, any such modified forms of structure or use of mechanical equivalents, as may be reasonably included within their scope.

I claim as my invention:

1. A flying toy gun comprising a tubular

member, laterally extending supports thereon, a shaft mounted in said supports for rotary and sliding movement, a block on said shaft, coacting engaging members on said block and one of said supports, a guide supported on said tubular member, a flexible device secured to said shaft and extended over said guide, a contractile spring in said tubular member, and a trigger device for engaging and sliding said shaft.

70

2. In a flying toy gun, a supporting device, a shaft rotatably and slidably mounted thereon, rotary members for forming bearings for said shaft, a block on said shaft, having engaging members, coacting engaging members on said block and said supporting member, a spring, a flexible device secured to said shaft and connected to said spring, and means for sliding said shaft longitudinally.

75

3. In a flying toy gun, a supporting device, a shaft rotatably and slidably mounted thereon, rotary members for forming bearings for said shaft, a block on said shaft, having engaging members, coacting engaging members on said block and said supporting member, a spring, a flexible device secured to said shaft and connected to said spring, and means for sliding said shaft longitudinally, and means for normally holding said 95 last means inoperative.

90

4. In a flying toy gun, a supporting device, a shaft rotatably and slidably mounted thereon, rotary members for forming bearings for said shaft, a block on said shaft, having engaging members, coacting engaging members on said block and said supporting member, a spring, a flexible device secured to said shaft and connected to said spring, means for sliding said shaft longitudinally, and means for normally holding said last means inoperative, and a device for moving said shaft moving means to position for engaging and moving said shaft.

100

5. In a device of the class described, a tubular member, laterally extending supports thereon, a shaft rotatably and slidably mounted on said supports, roller bearing devices for said shaft, a block on said shaft, coacting engaging means on said block and 115 said supports, means on said block and one of said supports for coacting engagement, engaging members for a flying toy on said block, a guide supported on said tubular member, a contractile spring in said tubular member, and a flexible device secured to said spring and extended over said guide and secured to said shaft.

115

6. In a device of the class described, a tubular member, laterally extending supports thereon, a shaft rotatably and slidably mounted on said supports, roller bearing devices for said shaft, a block on said shaft, coacting engaging means on said block and said supports, means on said block and one 125

130

Des Moines, Iowa. September 21, 1920.

FERDINAND H. SCHULTZ.
